UNITED STATES PATENT OFFICE.

CHARLES A. WHITNEY, OF STEVENSVILLE, PENNSYLVANIA.

FOLDING UMBRELLA.

SPECIFICATION forming part of Letters Patent No. 659,563, dated October 9, 1900.

Application filed December 29, 1899. Serial No. 741,964. (No model.)

To all whom it may concern:

Be it known that I, CHARLES A. WHITNEY, a citizen of the United States, residing at Stevensville, in the county of Bradford and 5 State of Pennsylvania, have invented certain new and useful Improvements in Folding Umbrellas; and I do hereby declare the following to be a full, clear, and exact description of the invention, such as will enable others skilled in the art to which it appertains to 10 make and use the same.

As is well known, the ordinary umbrella cannot be packed into a trunk, grip, or the like and cannot be reduced in length for convenience of handling and storing when not required for immediate use. Hence folding umbrellas have been devised to fulfil these 15 conditions, and the present invention is of this character and aims to provide an umbrella, parasol, and analogous device which 20 can be quickly reduced to a compact form for storage and carrying and as expeditiously arranged for use when required, the joints being stayed and of such a character as to 25 withstand strain in all directions and prevented from casual separation.

For a full description of the invention and the merits thereof and also to acquire a knowledge of the details of construction of 30 the means for effecting the result reference is to be had to the following description and to the drawings hereto attached.

While the essential and characteristic features of the invention are necessarily susceptible of modification, still the preferred embodiment of the invention is illustrated in the accompanying drawings, in which—

Figure 1 is a front view of a folding umbrella constructed in accordance with the 40 principles of the invention, the frame and cover being extended and broken away. Fig. 2 is a view of the frame and cover, showing the relation of the parts when the umbrella is folded. Fig. 3 is a side elevation of the 45 stick, the parts being separated. Fig. 4 is a longitudinal section of the joint formed between the sections of a rib, showing the upper section in full lines. Fig. 5 is a side elevation of the joint between the rib-sections, 50 the latter being alined. Fig. 6 is a view similar to Fig. 5, the upper section being broken

away to show the notched end of the lower section in engagement with the upper pivot-fastening. Fig. 7 is a vertical central section of the stick on a larger scale, parts being 55 broken away. Fig. 8 is a side elevation of the joint between the rib-sections, the latter occupying a folded position. Fig. 9 is a detail perspective view of the parts comprising the joint between the rib-sections, said parts 60 being separated. Fig. 10 is a plan view of the joint. Fig. 11 is a cross-section on the line 11 11 of Fig. 7. Fig. 12 is a transverse section on the line 12 12 of Fig. 7. Fig. 13 is a detail view of the joint formed between 65 sections of the stick when the latter is constructed from wood.

Corresponding and like parts are referred to in the following description and indicated in all the views of the drawings by the same 70 reference characters.

The umbrella in its general construction comprises the stick A, notch 1, cover 2, ribs B, braces 3, runner 4, and the usual catches for co-operation with the runner to hold the 75 umbrella open or closed. The ribs and stick are sectional, so as to admit of reducing the length of the umbrella and folding it in a compact package, the sections of the stick being separable and the sections of the ribs 80 foldable. The outer flange of the notch 1 is wider than the corresponding flange of the runner 4 to admit of the brace 3 folding between the stick and the upper section of the rib. 85

The ribs B are composed of an upper section 5 and a lower section 6, pivotally and loosely connected by means of a link 7 in such a manner as to admit of a relative outward movement of the section 6 when folding, whereby a space is formed between the sections to receive the cover without injuriously pinching it. The ribs are of the channeled type, and their meeting end portions fit the one within the other to secure a joint 90 of maximum strength. The upper end portion of the lower section 6 is cut away on the outer or folded side and is notched, as shown at 8, to receive the end portions of the pivot-fastening 9 when the sections 5 and 6 are 95 alined. A notch 11 is formed in the outer side of the lower end portion of the section 5 100

to receive the middle portion of the pivot 10. This construction admits of the close fitting of the overlapped portions of the sections 5 and 6 when the rib is extended. The cutting away of the terminal portion of the section 6 enables the link to be pivotally connected with the sections a short distance from their extremities and results in a maximum lap-joint.

10 The link 7 is of H form, the side bars 12 embracing the sides of the joint and the cross-bar 13 projecting over the joint and supplementing the action of the pivot-fastenings 9 and 10 in strengthening the joint when the umbrella is open. The end portions of the bars or members of the link are pivotally connected to the respective sections 5 and 6 by means of the pivot-fastenings 9 and 10.

15 The braces 3 are attached to the upper sections 5 at a point to admit of their folding about parallel with the stick and rib when the umbrella is closed. The pivot attachment may be effected in any manner, either direct or by means of a clip 14. The sections 20 when alined may be secured against displacement by means of a slide 15, which is moved so as to embrace the lower end of the section 5 and the section 6, upon which latter it is 25 slideable.

30 The stick A is composed of the tip 16, sections 17 18, and the handle 19, the parts being attached by a slip-joint and suitable fastenings. The catches for the tip 16 and sections 17 and 18 are alike. Hence a detailed 35 description of one will suffice. A plug 20 is secured to one of the parts and is grooved in a side to receive a spring-catch 21, which is secured at one end thereto. This catch is formed with a bent end 22 to pass through an 40 opening 23 in the matching part and with a projecting part 24 to be pressed upon by the thumb or finger when it is required to disconnect the parts. A stud a extends out from the projecting end of the plug 20 and cooperates with a groove 26 in the side of the part 45 into which the plug is fitted to properly position the parts and insure registry of the engaging end 22 of the catch and the opening 23.

The lower end of the section 18 is reduced 50 or provided with a plug to enter an opening in the end of the handle, and the latter is secured by means of a pin 27, passed through coincident openings in the parts comprising the joint. The end of the pin is threaded 55 and screws into a threaded opening in the side of the ferrule fitted to the end of the handle, said ferrule being likewise held in place by the pin, the latter having a head to be grasped when tightening and loosening it 60 by rotation.

The catch 28, applied to the section 17, has offstanding parts 29 and 30, the latter being a stop to limit the upward movement of the runner when opening the umbrella. The 65 part 29 serves as a catch to hold the umbrella open and as a finger-piece to be pressed upon

for operating the catch. When it is required to fold the umbrella, by moving the runner toward the peak or tip the part 29 is pressed upon to withdraw the stop 30 from out the 70 path of the runner, when the latter will move upward. The runner is grooved to pass by the finger-piece 24 of the catch 21 in both directions. When the ribs are extended and fixed by means of the slides 15, the umbrella 75 can be opened and closed in the usual manner. However, when it is required to reduce the length of the umbrella the slides are drawn back and the sections 6 folded upward upon the sections 5 and the parts 16, 18, and 80 19 are detached and wrapped in with the cover, as will be readily understood.

When the stick is constructed of wood, the end of one section is reduced and the corresponding end of the other section is bored to 85 receive the reduced end. A sleeve 31 overlaps and stiffens the joint. This construction is shown most clearly in Fig. 12.

Having thus described the invention, what is claimed as new is—

1. In a folding umbrella, a rib comprising upper and lower sections pivoted together and having the pivoted ends extended and adapted to overlap when the sections are alined, a link jointing the sections and composed of parallel plates embracing the sides of the said sections and pivoted at their extremities thereto and a cross-bar connecting the outer edges of said plates midway of their ends and adapted to lie between the rib-sections when folded and to supplement the overlapping ends of the sections to brace the joint between them when extended, and means for holding said parts rigidly connected when the rib-sections are in alinement, substantially as described.

2. In a folding umbrella, a rib comprising upper and lower channelled sections, the lower section being notched transversely in its folded side at its upper end to form parallel 110 hooks and the upper section similarly notched adjacent to its lower end to form a transverse seat-depression, a substantially H-shaped link composed of parallel side plates embracing the sides of the said sections and pivoted 115 at their extremities by pins passing through the sides of the sections and adapted to be respectively engaged by said hooks and to rest in said seat-depression when the rib-sections are alined, and a cross-bar connecting 120 the outer edges of the side plates intermediate of their ends and adapted to lie between the rib-sections when folded, and a slide 125 adapted to embrace the link to rigidly hold the parts connected when the rib-sections are in alinement, substantially as described.

In testimony whereof I affix my signature in presence of two witnesses.

CHARLES A. WHITNEY. [L. S.]
